CLAIM

The ornamental design for incontinence boxer shorts with internal pouch for absorbent pad, as shown and described.

DESCRIPTION

FIG. 1 is a plan view of the interior of the incontinence boxer shorts with internal pouch for absorbent pad of a first preferred embodiment of the present invention;

FIG. 2 is a side view of the internal pouch of the first preferred embodiment of the present invention;

FIG. 3 is a front end view of a portion of the waistband and of the internal pouch of the first preferred embodiment of the present invention;

FIG. 4 is a back end view of a portion of the waistband and of the internal pouch of the first preferred embodiment of the present invention;

FIG. 5 is a plan view of the exterior of the boxer shorts of the first preferred embodiment of the present invention;

FIG. 6 is a plan view of the interior of the boxer shorts of a second preferred embodiment of the present invention;

FIG. 7 is a plan view of the interior of the boxer shorts of a third preferred embodiment of the present invention;

FIG. 8 is a plan view of the interior of the boxer shorts of a fourth preferred embodiment of the present invention;

FIG. 9 is a plan view of the interior of the boxer shorts of a fifth preferred embodiment of the present invention; and,

FIG. 10 is a plan view of the exterior of the boxer shorts of the fifth preferred embodiment of the present invention.
